W. L. MILLIORN.
LIFTER AND TURNER.
APPLICATION FILED JUNE 30, 1917.

Patented Feb. 12, 1918.

Inventor
W. L. Milliorn
By *Amelia J. Jones*
Attorney.

UNITED STATES PATENT OFFICE.

WILLIAM L. MILLIORN, OF EL PASO, TEXAS.

LIFTER AND TURNER.

1,256,245.

Specification of Letters Patent. Patented Feb. 12, 1918.

Application filed June 30, 1917. Serial No. 177,900.

To all whom it may concern:

Be it known that I, WILLIAM L. MILLIORN, a citizen of the United States, residing at El Paso, in the county of El Paso and State 5 of Texas, have invented certain new and useful Improvements in Lifters and Turners, of which the following is a specification, reference being had therein to the accompanying drawing.

10 This invention relates to a lifter and turner, comprehending the provision of a simple, convenient and handy utensil for lifting pots, pans, kettles and lids, and for turning and lifting articles of food, etc., 15 the object of the invention being to provide a device which may be inexpensively manufactured and which will effectually serve its intended purpose. The invention consists of the features of construction, combination 20 and arrangement of parts hereinafter fully described and claimed, reference being had to the accompanying drawing, in which:—

Figure 1 is a perspective view of a lifter and turner constructed in accordance with 25 my invention.

Fig. 2 is a transverse section through the lifting blade on the line 2—2 of Fig. 1.

Fig. 3 is a side elevation of the device as employed for lifting a pan or similar utensil.

30 Fig. 4 is a view of a portion of the handle of the device showing its use as a lid or like lifter.

Fig. 5 is a central longitudinal section through the lifting blade.

35 In carrying my invention into practice, I provide a lifter and turner, comprising a lifting and turning blade or plate 1, made of sheet metal or other suitable material. This blade is substantially pear-shaped, be- 40 ing of maximum width at or near the rear end thereof and thence tapering to substantially a point at its forward end, the reduced end of the blade being adapted to be conveniently inserted under an object to be lift- 45 ed or lifted and turned. The blade when made of sheet material is preferably provided with a central longitudinally extending rib or corrugation 2, whereby it is stiffened and strengthened to a desired extent.

50 A looped handle 3 is provided for manipulating the blade or plate. This handle 3 is composed of two strands 4 and 5 of wire of suitable gage. The intermediate portions of these wires are disposed in parallel relation and intertwined to provide the looped handle body 6, and a portion thereof is also

bent to form a depending lifting hook 7 at the rear end of the handle. At the forward end of the handle the intertwined wires are arranged to provide a shank or neck 8', and from this shank or neck the terminals or end portions of the wires are bent and extended for attachment to the blade.

As shown, the ends 8 of the wire 4 are arranged to extend forwardly beneath the rear portion of the body of the blade in divergent relation, and these ends 8 of the wire 4 are preferably flattened and secured to the blade by rivets or other suitable fastenings 9. The ends 8 are disposed on opposite sides of the medial or center line of the blade, and by their diverging relationship form a firm connection, whereby the shank of the handle is fastened to the blade in a staunch and durable manner.

The ends of the wire 5 are bent outwardly in opposite directions to form segmentally curved stop arms 10, which are disposed above and slightly in rear of the rear edge 80 of the blade 1 and curved to conform to the contour of such portion of the blade, said arms thence being bent downwardly to provide vertical stop shoulders 11, and finally bent forwardly and inwardly on converging lines to provide attaching portions 12, which attaching portions 12 extend beneath the side portions of the blade or plate 1, at a point in advance of the ends 8 of the wire 4 and between the same and the transverse center of the blade and are secured to the blade by rivets or other suitable fastenings 13.

By the construction described, the terminals of the wire 5 form braces which are connected with the sides of the blade in advance of and laterally beyond the attaching ends 8 of the wire 4, whereby a form of fastening connection between the blade and handle is afforded, thus preventing the blade 100 from having pivotal motion on the fastening connections and causing the same to work loose, and also adapting the blade and handle to support weighty pots, pans or other articles without subjecting the handle 105 or fastening parts to undue strain. The arms 10 and shoulders 11 also form stop members to embrace the rear portion of a pan 14, pot or other similar vessel, whereby the same may be held securely against shifting in any direction while being lifted and transported. The bracing arms and shoul-

ders furthermore adapt the blade to be inserted beneath the bottom of a pan and the pan shifted rearwardly by tilting the lifter and pan, without the necessity of handling the pan or liability of the pan becoming displaced.

It will be understood that the device may be used as a lifter for various kinds of pots, pans, and cooking or other utensils, whereby 10 hot utensils may be lifted, handled and transported in an easy and convenient manner. The blade 1 may also be employed as a lifter and turner for cakes, hot potatoes and other food stuffs. By reversing the tool 15 in the hand the hook 7 may be engaged with the handle 15 of a lid or cover 16, or other similar object, whereby a hot lid or cover may be applied and removed in a simple and convenient manner.

20 It will thus be seen that my invention provides a device of the character described which is simple of construction, convenient and efficient in action, and which may be manufactured and sold at a comparatively. 25 low cost. When not in use the device may be hung up or suspended by means of the looped handle 6 or hook 7, as will be readily understood.

Having thus fully described my invention, 30 I claim:

1. A lifter and turner comprising a lifting and turning plate, a handle formed of looped and twisted strands of wire, certain

end portions of one of the wires being arranged in diverging relation and secured to 35 the plate, the other wire being twisted about the first named wire and extended to provide bracing arms disposed rearwardly of the plate and also bent to provide stop shoulders arranged rearwardly of the points of 40 attachment of the first named wire to said plate.

2. A lifter and turner comprising a lifting and turning plate and a handle formed of a pair of looped and twisted strands of 45 wire, said strands being constructed to provide a looped handle proper, and a shank at the forward end of the handle proper, and one of the wires having end portions secured to the plate on diverging lines adjacent to its longitudinal center, and the other wire having its end portions formed to provide laterally extending bracing arms disposed above and projecting along the rear portion of the plate, said arms having depending portions forming stop shoulders and terminal portions projecting inwardly on converging lines and secured to the plate at points in advance and outwardly beyond the attaching ends of the first named wire. 50

In testimony whereof I hereunto affix my signature in the presence of two witnesses.

WILLIAM L. MILLION.
